[57] ABSTRACT

Freshly made concrete blocks are placed on racks which are suitably disposed in a kiln and steam is introduced by means of a syphon which communicates with the atmosphere and causes the transmittal of the steam along with air which results in the "green" blocks being capable of withstanding higher temperatures than would otherwise be the case; the elements in the air imparting increased tendency of the cement to set and harden.

APPARATUS FOR CURING BUILDING BLOCKS

It is among the objects of the invention to attain a uniform temperature throughout the curing kiln which results in cured concrete blocks which possess higher compressive strength than is obtainable by conventional methods over the same period of time, whether it be overnight, or at 7 and 28 day periods.

Another object is the reduction of shrinkage in the cured concrete blocks.

Still another object is to provide a steam treatment for the purposes described wherein less steam is required than would otherwise be the case.

A further object is to attain the foregoing ends with apparatus which is durable in service, and inexpensive to install, operate and maintain.

Still further objects, and the nature and advantages of the invention, are made clear in the following description, and the annexed drawings present the best form of the invention presently known to me. However, this disclosure is by way of example only, and changes not shown herein may be made without deviation from the principles of the invention of material alteration of any of the essential characteristics as defined in the appended claims.

In said drawings:

FIG. 1 is a fragmentary elevational view, partly in section, which discloses an operative embodiment of the apparatus of the invention; and

FIG. 2 is an enlarged fragmentary elevational view illustrating the inner and outer pipes or tubes which communicate with the interior of the curing kiln for purposes which will be later described.

Referring more particularly to the drawings, the curing kiln of the invention comprises a floor 3, sidewalls 4, backwall 6, front opening provided with a door (not shown) and a roof 12; all of which are made of suitable materials in the manner known in the art.

Adjacent the bottom of the backwall 6 is a horizontally extending circular aperture which receives a pipe or tube 14, the latter projecting from the outer surface of the backwall and being connected to one end of the line passage of a Tee-fitting 18.

The other end of the line passage of the Tee-fitting 18 is provided with a closure plate 22 having therein a centrally disposed aperture of considerably lesser diameter.

Concentrically disposed in the pipe 14 is a pipe or tube 24 of substantially smaller diameter. This inner pipe 24 terminates short of the inner end of the larger pipe 14, as shown.

Adjacent the inner end of the inner pipe 24 and on its outer surface is a series of jet mixing fins 28 which are angularly disposed with respect to the axis of this pipe.

The outer end of the inner pipe 24 projects for an appreciable distance from the centrally apertured closure plate 22 on the fitting 18 and is connected to elbow 30 which communicates with the lower end of a vertically disposed pipe 32. The upper end of the vertically disposed pipe extends above the roof 12 of the kiln and is connected, through an elbow 34, with a steam main 36, which communicates with a suitable steam boiler (not shown) and is provided with an electrically operated valve 38.

This electrically operated valve 38 is controlled through a thermostatic switch generally indicated at 40.

Further control of the steam which is supplied to the inner pipe 24 is provided by a valve 42 in the vertically disposed pipe 32.

The branch of leg portion of the Tee-fitting 18 is connected to the bottom of a vertically disposed pipe 46, the upper end of which terminates into proximity with the roof 12 and is connected through an elbow 48 with a pipe 50 which extends through the backwall 6 and projects therefrom into communication with the upper portion of the interior of the kiln.

A valve 52 in the vertically disposed pipe 46 permits the introduction of atmospheric air and controls the quantity of air introduced.

In the operation of the apparatus, freshly made blocks of concrete are placed on racks (not shown) which are placed within the curing kiln 2; and steam is supplied through the steam main 36, vertically disposed pipe 32, Tee-fitting 18 and inner pipe 24 into the kiln adjacent its bottom. As this is done, outside air is pulled into the kiln through valve 52 by syphon action of inner pipe 24 located in outer pipe 14.

The steam and outside air mixture, after flowing through the kiln in the manner illustrated by the arrows, leaves the upper portion of the kiln through the horizontal pipe 50, and it pulled through syphon action through the vertically disposed pipe 46, and branch or leg portion of the Tee-fitting 18, around the exterior of the inner pipe 24 and moves between the angularly disposed tapering jet mixing fins 28 and out of the inner end of the horizontally extending pipe 14 back into the kiln, causing forced circulation action therewithin.

A suitable quantity of atmospheric air is supplied to the outer pipe 14 through the valve 52 in the vertically disposed recycling pipe 46; and steam is provided through inner pipe 24 at a pressure which may be acceptably around 60 pounds per square inch, this being more or less based on the size of the kiln.

Steam at a suitable pressure results in the syphoning into the kiln of an appreciable amount of atmospheric air, which permits the use of higher and more even temperature in the curing process.

The higher temperature within the kiln, and the mixture of steam and atmospheric air result in

1. Attainment of uniform temperature throughout the kiln in a manner which is much quicker than in the case of conventional kiln which have steam injected thereto, but wherein no atmospheric air is introduced. 2. Much greater compressive strength in the cured blocks overnight, as well as at intervals of 7 days and 28 days. 3. Reduced shrinking of the cured concrete blocks, and 4. The requirement of less steam.

Having thus described the invention, what I claim as new and desire to secure by Letters Patent is:

1. Apparatus for curing cementitious articles such building blocks which comprises
a kiln for receiving the cementitious articles said kiln having an intake port and an exhaust port
a steam supply pipe of substantially smaller diameter extending into the intake port and in axial alignment therewith
a conduit communicating with said exhaust port and with the space between the inner surface of said intake port and the outer surface of the steam pipe which is disposed coaxially therein and
means for supplying atmospheric air to said conduit

the inner end of said steam supply pipe terminating short of the inner end of said intake port in which it is coaxially disposed, to thereby produce a siphoning effect on the recirculating steam and atmospheric air moving through the space between the outer surface of said steam supply pipe and the inner surface of said intake port.

5

2. The apparatus of claim 1, together with means disposed between the inner wall of said intake port and the outer wall of said steam pipe for imparting a swirling motion to the mixture of steam and gas passing therethrough.
